UNITED STATES PATENT OFFICE

140,795

DESIGN FOR AN AIRPLANE

Hall L. Hibbard, West Los Angeles, and Clarence L. Johnson, Encino, Calif., assignors to Lockheed Aircraft Corporation, Burbank, Calif.

Application November 26, 1943, Serial No. 111,793

Term of patent 14 years

(Cl. D71—1)

To all whom it may concern:

Be it known that we, Hall L. Hibbard and Clarence L. Johnson, citizens of the United States, residing at West Los Angeles and Encino, respectively, both in the county of Los Angeles and State of California, have invented a new, original, and ornamental Design for an Airplane, of which the following is a specification, reference being had to the accompanying drawings, forming a part thereof:

Figure 1 of the drawings is a perspective view of an airplane embodying the new design as it would appear from a point off to the side and

slightly forward and above the airplane while in flight with its main and nose landing wheels retracted;

Figure 2 is a side elevational view of the subject airplane;

Figure 3 is a top plan view thereof;

Figure 4 is a front elevational view thereof.

We claim:

The ornamental design for an airplane, substantially as shown.
